UNITED STATES PATENT OFFICE.

ROBERT F. FERGUSON, OF CEDAR RAPIDS, IOWA, AND THOMAS E. BARNES, OF DULUTH, MINNESOTA.

SANITARY HEAD-COVERING.

1,258,550.

Specification of Letters Patent.

Patented Mar. 5, 1918.

Application filed April 7, 1917. Serial No. 160,566.

To all whom it may concern:

Be it known that we, ROBERT F. FERGUSON and THOMAS E. BARNES, citizens of the United States, residing, respectively, at Cedar Rapids, in the county of Linn and State of Iowa, and at Duluth, in the county of St. Louis and State of Minnesota, have invented certain new and useful Improvements in Sanitary Head-Coverings, of which the following is a specification.

This invention relates to a head covering in the nature of a skull-cap, made of a material so inexpensive as to admit of its being thrown away after a single use, and necessarily limited in its construction to paper, or the like.

The primary object of the invention is to provide a simple, cheap, sanitary cap which may be employed by milliners and to some extent by dentists, in waiting on their customers. It is more especially useful to milliners, inasmuch as in fitting hats there is the repeated trying on of the article, which sometimes results in the hopeless soiling of the lining, often of fine and expensive material. There is also the danger, now more and more recognized, of infection by dandruff, or other transmissible scalp disorders, for which the cap is a preventive.

In the accompanying drawing, forming a part of this specification, Figure 1 illustrates the application of the cap in connection with a lady's hat. Fig. 2 is a side view of a cap embodying the invention. Fig. 3 is a view of the inside of the same as expanded. Fig. 4 shows the same device as Fig. 2, but with a different fastening of the edges.

The device is very simple, consisting of a pair of semicircular sheets of paper, A and B suitably fastened together at the upper curve, as the curve C may be designated. This fastening may be by stitching, as shown at D, or, if suitable material is used, by pasting, as indicated at E, Fig. 4. Preferably the lower edges F should be curved outwardly somewhat, so that when the cap

is opened out they assume a practically level position. Preferably the paper should be of the sort embossed to imitate crêpe, or a like nature, which allows for considerable stretch when applied to the head. This is the more necessary from the fact that in practice it is most convenient to have but one size, and this should be adaptable to all sizes of heads and hair-dressing. Its use is clearly indicated in Fig. 1, being opened out and drawn down over the hair enough to protect the hat and its lining, but with a slight and inconspicuous edge below the hat, not sufficient to detract from the set or becomingness of the article. Once used, the paper cap is thrown away, and a clean one taken for each succeeding customer.

The device is capable of being packed perfectly flat, and in a convenient shape for shipment and use.

Having thus described our invention, we claim:

1. A sanitary head covering, composed of a pair of substantially semicircular sheets of paper attached together along the upper curved edge.

2. A sanitary head covering, composed of a pair of substantially semicircular sheets of paper attached together along the upper curved edge, the opposite edges being curved to a longer radius, substantially as and for the purpose set forth.

3. A sanitary head covering, composed of a pair of substantially semicircular sheets of stretchable paper, such as crêpe paper, suitably attached to each other along the upper curved edge.

In testimony whereof we affix our signatures in presence of two witnesses.

ROBERT F. FERGUSON.
